(57) **CLAIM**

The ornamental design for a transportable and stackable storage container, as shown and described.

DESCRIPTION

FIG. 1 is a top perspective view of a transportable and stackable storage container embodying my design, with the juncture between adjacent sidewall panels, the door hinges, the door lock mechanism, the towing clevises, the rollers, the bracing along the underside of the bottom wall, and the forklift sleeves being shown in broken lines for illustrative purposes only and forming no part of the claimed design;

FIG. 2 is a bottom perspective view of the transportable and stackable storage container depicted in FIG. 1;

FIG. 3 is a side elevation view of the transportable and stackable storage container depicted in FIGS. 1 and 2, with the opposite side elevation view being a mirror image thereof;

FIG. 4 is an end elevation view of the transportable and stackable storage container depicted in FIGS. 1-3;

FIG. 5 is an end elevation view of the transportable and stackable storage container opposite that depicted in FIG. 4;

FIG. 6 is a top elevation view of the transportable and stackable storage container depicted in FIGS. 1-5;

FIG. 7 is a bottom elevation view of the transportable and stackable storage container depicted in FIGS. 1-6; and,

FIG. 8 is a top perspective view of the transportable and stackable storage container depicted in FIGS. 1-7, but illustrating the container stacked on top of another similarly designed container for environmental purposes, with the lower container being shown in broken lines for illustrative purposes only and forming no part of the claimed design.
